UNITED STATES PATENT OFFICE

162,846

CLOCK PENDULUM OR SIMILAR ARTICLE

Alan E. Koplar, Chicago, Ill.

Application January 28, 1950, Serial No. 7,542

Term of patent 7 years

(Cl. D42—10)

To all whom it may concern:

Be it known that I, Alan E. Koplar, a citizen of the United States and a resident of Chicago, in the county of Cook and State of Illinois, have invented a new, original, and ornamental Design for a Clock Pendulum or Similar Article, of which the following is a specification, reference being had to the accompanying drawing, forming a part thereof.

On the drawing:

Figure 1 is a front elevational view of a clock pendulum or similar article, showing my new design; and

Figure 2 is a top plan view thereof.

I claim:

The ornamental design for a clock pendulum or similar article, as shown.

ALAN E. KOPLAR.
